UNITED STATES PATENT OFFICE.

JOHN W. WATKINS, OF PHILADELPHIA, PENNSYLVANIA.

SHEET-METAL WINDOW-SASH.

No. 812,467.

Specification of Letters Patent.

Patented Feb. 13, 1906.

Application filed January 21, 1905. Serial No. 242,176.

To all whom it may concern:

Be it known that I, JOHN W. WATKINS, of Philadelphia, in the State of Pennsylvania, have invented certain new and useful Improvements in Sheet-Metal Window-Sashes, whereof the following is a specification, reference being had to the accompanying drawings.

My invention relates to sheet-metal window-sashes which are divided by munnions and muntins into separate panes, and more particularly to the means for supporting the muntins in such sashes.

While the word "munnion" is frequently used as a name for the bars, whether horizontal or vertical, by which the sash is divided into panes, yet in this specification and in the claims for the sake of more accurate distinction I will use the words in what I understand to be their strict technical sense, in which the word "munnion" is confined to the vertical bar or bars and the word "muntin" to the horizontal bars by which the sash is subdivided.

Hitherto in sheet-metal window construction it has been customary to build the sash with munnions integral from top to bottom, each munnion being provided on both sides with the usual pane-grooves corresponding to the grooves on the interior of the rails of the sash. The muntins for the further horizontal subdivision of the pane-spaces thus created have been arranged to fit snugly against the opposing edges of the side rails or munnions, but have not been permanently secured thereto, being left movable in order that when the glass for the lower pane has been inserted the muntin may be laid above said pane and then another pane slid into the grooves on top of this, and so on. There is an advantage in such construction resulting in some saving of glass, since small differences in the vertical height of the pane may be disregarded and will adjust themselves in putting together the entire sash. There is, however, a disadvantage resulting from the failure to permanently secure the muntins in a fixed position within the sash by reason of the fact that if left unsecured upon the breaking or melting of a lower pane the removal of the support for the muntin above it allows it to slide down with the panes above it, usually occasioning further damage. My invention is directed toward the overcoming of this difficulty without the loss of the advan-

tage of the separable construction and provides a simple means by which the muntins may be adjustably secured in any desired position according to the height of the pane beneath them, at the same time providing a sufficiently firm support at each end of the muntin to prevent its falling when the pane below is broken or burned out.

I have shown in the accompanying drawings a number of modifications of which my invention is susceptible, all of which, however, have this in common: They have a wire or strip or other support secured to the sash bent in such form as to support the muntin above the underlying pane.

In the accompanying drawings, Figure I is a front elevational view of a sheet-metal window-sash arranged to conveniently embody various forms of my invention. Fig. II is a horizontal sectional view of a munnion, taken on the line II II in Fig. I, showing the integral supporting-piece slit from the webs which form the bottom of the grooves and bent to form horizontal muntin-supports. Fig. III is a horizontal sectional view of a side rail, taken on the line III III in Fig. I, showing the integral supporting-piece slit from the side wall of the groove and bent to form a horizontal support. Fig. IV is a vertical sectional view taken on the line IV IV in Fig. II. Fig. V is a vertical sectional view taken on the line V V in Fig. III. Fig. VI is a horizontal sectional view of the munnion similar to Fig. II, showing a separable supporting-piece in the form of a sheet-metal strip passing through the munnion and upturned at its extremities to engage the muntins. Fig. VII is a horizontal sectional view of a side rail similar to Fig. III, showing a separable supporting-piece in the form of a sheet-metal strip engaged with the rail and upturned at its extremities to engage the muntin. Fig. VIII is a vertical sectional view taken on the line VIII VIII in Fig. VI. Fig. IX is a vertical sectional view taken on the line IX IX in Fig. VII. Fig. X is a horizontal sectional view of a munnion similar to Fig. II, showing a separable supporting-piece in the form of a wire of circular cross-section passing through the munnion and bent to form a horizontal support for the muntins on each side. Fig. XI is a horizontal sectional view of a side rail similar to Fig. III, showing a separable supporting-piece in the form of a wire of circular cross-section engaged with the rail and hav-

ing its extremity upturned to engage an aperture in the muntin. Fig. XII is a vertical sectional view taken on the line XII XII in Fig. X. Fig. XIII is a vertical sectional view taken on the line XIII XIII in Fig. XI. Fig. XIV is a broken horizontal sectional view of a munnion and side rail, showing separable supporting-pieces in the form of continuous wires extending from one munnion to the next or to the side rail and conveniently secured at both ends. Fig. XV is a vertical sectional view taken on the line XV XV in Fig. XIV. Fig. XVI is a perspective view broken in the middle of the supporting-piece shown in Figs. XIV and XV. Figs. XVII to XXII are detail perspective views of differing forms of supporting strips or wires embodying my invention.

In Figs. I to V, I have illustrated my invention in a simple form. 1 is a window-sash comprising the side rails 2, the bottom rail 3, and the meeting-rail 4. 5 is a munnion, and 6 6 are muntins.

In Fig. II is shown a horizontal section of this munnion with the panes fitting its grooves on either side. It will be observed that this munnion is shown as formed by the bending and interlocking of two pieces of sheet metal, so as to form the two pane-grooves with a thin partition between them, and the union of the two parts is effected by the interclenching of the projecting webs of the two parts by which the partition between the pane-grooves is formed. This construction forms no part of my present invention, as it forms part of a previously-filed application. It will be understood that my present invention is applicable to sheet-metal sashes generally irrespective of the method by which the parts are put together. Before the glass is inserted in the sash flaps 7 7 are cut in the web which forms the outside of the partition between the grooves. These flaps are capable of being bent down to a varying depth, according to the size of the panes. When the two lower panes have been inserted, (for which purpose the meeting-rail may be provided with a slot,) the flaps 7 7 are bent down over the top of the panes. I have shown the flaps only in connection with the munnion; but it will of course be understood that a similar flap is cut into and bent down from the pane-groove of the side rails of the sash. The muntins are then slid down on top of the panes resting upon the bent cut flaps, and the upper panes are then slid into place and the sash completed. If now a lower pane be broken out, the flaps at either end of the muntin will support it from falling notwithstanding the absence of the pane below it.

In Figs. III and V a similar construction is shown, except that the flap 8 is of a slightly-different shape, and instead of being bent out from the partition between the grooves it is cut into and bent out from one of the side

walls of the pane-groove. I have illustrated the flap here in connection with the side rail of the window; but it will be understood that flaps are to be cut in the munnion.

In Figs. VI to IX, I have illustrated a construction in which in the place of flaps cut from the pane-grooves there are employed separate strips bent so as to engage the muntin or the side rail and projected to pass below the muntin and support it. 75

In Figs. VI and VIII, 5 is the munnion. At a point near where the junction with the muntins is expected to take place the partition between the pane-grooves is pierced with an aperture 10, and through this is inserted a flat metal strip 11. (See Figs. XVII to XIX.) This strip is not inserted until the lower panes have been put in place. It is then passed through the aperture, and unless the aperture 10 coincides precisely with the top of the panes it is bent until it reaches to the top of the pane. It is then bent out along the top of the pane, taking the shape shown in Fig. XVII. When the muntin is slid down over the pane, it rests upon the projecting portions of the strip. If desired, the extremities may be bent upward again, as shown in Figs. VI, VIII, and XIX, and the muntin provided with holes 12, into which its bent ends enter and over which they may be clenched. It will be thus seen that by this simple device the muntins are firmly locked to the munnion on each side. In Fig. XVIII the strip 19 is shown in the shape which it assumes when the aperture 10 coincides with the top of the panes. 90

In Figs. VII, IX, and XXI, I have shown a similar strip applied to the side rail of the sash. Here the entering end of the strip 17 is bent up and down, and after passing through the aperture 13 in the bottom wall of the pane-groove is drawn so as to clench within it. The external portion of the strip is then bent along the pane-groove until it reaches the top of the pane. It is then bent out along the edges of the pane and passed up through a hole 12 in the muntin and may be clenched, as shown. 105

In Figs. X to XIII, I have shown a similar construction, except that a simple bent wire is employed instead of the strip 11. Thus, referring to Figs. X and XII, a hole 14 is pierced through the munnion and the wire 15 inserted in the hole and bent on either side until it reaches the top of the lower panes and then bent out, so as to afford a support for the muntins. 115

Figs. XI, XIII, and XXII illustrate a similar wire 18 applied to the side rail passing through an aperture 16 and being clenched within the rail and also bent down along the groove to the top of the pane as before. 125

In Figs. XIV to XVI, I have illustrated a slightly-differing construction, in which instead of separate wires or strips at either side 130

of the pane a single wire 20 is caused to engage the pane-groove on both sides and is stretched across underneath the muntin and supports it. This is a stronger construction than the others and may be employed where the panes are very large or the glass very heavy. In Figs. XIV and XV, 5 is the munnion, and 2 the side rail. The pane-grooves of both of these are pierced to receive the wire 20. This wire enters these apertures, and thus engages both the pane-grooves at its extremities near the top of the lower pane and is immediately bent until it rests upon the top of the pane. The muntin when slid down upon it rests on the wire 20 instead of on the pane.

Having thus described my invention in several different forms, I desire it to be understood that it is capable of much further variation and that the forms described by me are intended to be but examples of some different ways of embodying it. Furthermore, under some circumstances two or more of the forms described by me may be used in conjunction. Thus where a flap 8 bent from the side of the pane-groove is employed an auxiliary strip clenched upon the flap and also to the muntin, as, for example, shown in Fig. IX, may be employed. Other combinations will also suggest themselves at once to one skilled in the art as carrying out my invention. In all there is a common principle—to wit, a supporting-piece for the muntin either integral with or attached to the munnion (or the side rail, as the case may be) and capable of being accurately adjusted so as to pass under the muntin to support it

in the upper position according to the size of the pane below it.

I claim—

1. In a sheet-metal window-sash, a muntin-support consisting of a flexible piece secured to the munnion (or side rail) and having its free end projected to pass under and support the muntin, substantially as set forth. 40

2. In a sheet-metal window-sash an adjustable muntin-support secured to the munnion (or side rail) and bent to reach the top of the pane and then bent out along the top 50 of the pane to afford a support for the muntin which rests on top of the pane, substantially as set forth.

3. In a sheet-metal window-sash, a muntin-support consisting of a piece of metal attached to both the munnion and the muntin, and bent so as to support the muntin at its juncture with the munnion at the proper height to accommodate the pane below it, substantially as set forth. 55

4. In a sheet-metal window-sash, a muntin-support consisting of a flexible strip passing through the partition between the pane-grooves of the munnion, and passing under the extremities of the muntins when they 65 abut against the munnion on either side, substantially as set forth.

In testimony whereof I have hereunto signed my name, at Philadelphia, Pennsylvania, this 17th day of January, 1905.

JOHN W. WATKINS.
